(57) **CLAIM**

The ornamental design for a doorbell bracket, as shown and described.

DESCRIPTION

FIG. 1 shows a lower, front, right perspective view of a doorbell bracket;

FIG. 2 shows an upper, right, rear perspective view thereof;

FIG. 3 shows a front view thereof;

FIG. 4 shows a rear view thereof;

FIG. 5 shows a left side view thereof;

FIG. 6 shows a right side view thereof;

FIG. 7 shows a top view thereof; and,

FIG. 8 shows a bottom view thereof.

The dash-dash broken lines illustrate portions of the doorbell bracket that form no part of the claimed design. The dash-dot broken lines illustrate the bounds of the claim that form no part of the claimed design.

1 Claim, 7 Drawing Sheets
